UNITED STATES PATENT OFFICE.

MORRIS GOTTLIEB, OF PHILADELPHIA, PENNSYLVANIA.

SPARK-PLUG.

1,374,847.

Specification of Letters Patent. Patented Apr. 12, 1921.

Application filed February 10, 1919. Serial No. 276,064.

To all whom it may concern:

Be it known that I, MORRIS GOTTLIEB, a citizen of the United States, residing at 2644 South 8th street, Philadelphia, in the 5 county of Philadelphia and State of Pennsylvania, have invented new and useful Improvements in Spark-Plugs, of which the following is a specification.

The invention relates to spark plugs and 10 has for an object to provide a spark plug for use in exploding the gas or gases, particularly in connection with the combustible gas in an internal combustion motor, and in which the electrodes of the spark plug will 15 be protected to prevent undue accumulation 5 of carbon deposit or oil, thereby increasing the value and intensity of the spark produced.

Among other features, the invention 20 comprehends the provision of a spark plug, which can be cheaply manufactured and which consists of few and simple parts that can be readily assembled, the main feature however, comprising a conical hood or cover 25 for the open end of the jacket, which hood or cover forms the ground electrode, the conical configuration of the cover whereby the side wall thereof will be inclined, preventing any accumulation of oil at the apex 30 of the conical cover and which apex forms or is a part of the ground electrode.

In the further disclosure of the invention, 35 reference is to be had to the accompanying drawings, constituting a part of this specification in which similar characters of reference, denote corresponding parts in all the views, and in which,—

Figure 1— is a vertical sectional view taken through the spark plug.

40 Fig. 2— is a bottom plan view, and

Fig. 3— is a fragmentary vertical sectional view of a slightly modified form.

Referring more particularly to the views, 45 the numeral 10 indicates a jacket which may be suitably threaded as at 11, and has disposed therein a porcelain holder 12, carrying a main electrode 13, which passes through the holder and is insulated from the jacket thereby, said electrode 13 having a projecting end 14, adjacent the lower end of the jacket, with a suitable nut 15 threaded into the jacket to secure the porcelain holder rigidly in place.

The lower or open end of the jacket 10 is 55 closed by a cover or hood 16, and attention is particularly called to the configuration of

the hood, namely that it is of a conical formation. The hood along its peripheral edge may be secured in any desired manner, to the lower extremity of the jacket, and by reason of its conical formation, it extends upwardly in the jacket to a point adjacent the projecting end of the main electrode 13. The cover is formed with a plurality of openings 17, which it will be noted extend substantially at right angles to a conical wall, and through the same, and it will be seen that the apex of the hood or cover, spaced slightly from the projecting end of the main electrode, forms a second or ground electrode 18. Although the conical formation of the hood or cover naturally will form an apex, it will be noted that at this point the hood is slightly indented to form an upwardly projecting tit indicated 65 by the numeral 19, and this formation, it will be seen conforms to the configuration of the side wall of the hood or cover, so that any oil or other deposits on the ground electrode or apex, will be drained therefrom by 70 the conical configuration of the hood and will pass out through the apertures 17.

In Fig. 3, it will be seen that I provide a slightly modified form, wherein instead of having the tit 19 formed integral with the 75 hood or cover, I make the same in a separate piece, indicated by the numeral 20, provided with a threaded stem 21, threaded through an opening 22 in the apex of the hood or cover with a plurality of locking 80 nuts 23 threaded onto the stem to secure the tit 20 in rigid position. It will be seen that with this construction the tit or ground electrode can be readily adjusted to be brought closer to or farther away from the 85 projecting end of the main electrode 13.

I am aware that various forms of spark plugs have been used heretofore, which comprehend inclosing the lower part of the jacket for the purpose of preventing the 90 accumulation of oil or carbon on an electrode, and I am also aware of various forms of attachments that have been used in an endeavor to accomplish this purpose. I have found however, from actual experience, that with a construction such as I have set forth, I obtain what might be termed a self-draining spark plug, in that the ground or secondary electrode will be kept substantially free from carbon or oil 95 deposits already received, by the conical formation thereof and which, on account of 100 105 110

the steep angularity of the wall, causes the carbon or oil deposit to be drained or jarred from the contact point in the use of the plug.

5 Still further it will be seen that any oil splashing up against the bottom of the spark plug will be prevented, due to the conical formation of the cover or hood, from obtaining access to the interior of the 10 jacket or the contact point of the cover, and will drain down the outside of the cover so as to keep the contact point clean, and thus permit of obtaining a hot and intense spark.

I wish it to be understood that I do not 15 claim to be the first person to inclose the open end of the jacket of a spark plug, but I have found that the ordinary closures generally employed are not sufficient to accomplish the purpose and that it is necessary to provide a construction whereby the 20 lower electrode will be of an upstanding nature, and of a conical or pyramidal shape so as to form draining surfaces from the apex thereof.

Having described my invention, I 25 claim,—

A spark plug comprising an outer metallic body, a body of insulation within said metallic body, an electrode extending centrally through said body of insulation and terminating considerably short of the end 30 of the metallic body, a frusto-conical metallic shell secured to and extending into the open end of the metallic body and having its smaller end closed and formed with a 35 threaded hole and having its peripheral wall apertured, a conical electrode point disposed upon the small end of said frusto-conical shell and carrying a threaded stem screwed into said hole whereby the conical 40 electrode point may be adjusted toward or from the end of said first named electrode, and lock nuts on said stem within the frusto-conical shell whereby to lock the conical point in adjusted position. 45

In testimony whereof I affix my signature.

MORRIS GOTTLIEB.
